UNITED STATES PATENT OFFICE

CRAWFORD C. LOOMIS, OF ILION, NEW YORK, ASSIGNOR TO REMINGTON ARMS COMPANY, INC., A CORPORATION OF DELAWARE

FIREARM

Application filed May 10, 1930. Serial No. 451,241.

The present invention relates to firearms, and has for its special object the provision of improvements in firearms of the type disclosed in the patents to J. D. Pedersen, No. 5 719,955 of February 3, 1903, and No. 789,755 of May 6, 1905, and in the patent to C. C. Loomis, No. 1,579,177 of March 30, 1926. A firearm of the type disclosed in these patents embodies a breech block movable rearwardly 10 and downwardly, from a position in front of the barrel chamber to a retracted position in the receiver, by operation of an action bar connected to a reciprocable forearm. The firing mechanism of this type firearm comprises a longitudinally slidable firing pin which is carried by the breech block and is spring urged to its firing position. A cocking head integral with the rear portion of the firing pin is adapted to be moved rearwardly 15 relative to the breech block on retraction of the forearm and action bar, and is adapted to be engaged and held in its rearward position by a trigger operated sear carried by the breech block. Movement of the breech block 20 25 and cocking of the firing pin is effected on retraction of the action bar by a connection between the action bar and breech block, comprising a lug integral with the action bar adapted to ride in a cam groove formed in one 30 side of the breech block, the lug being adapted also to engage a cam surface on the cocking head for cocking the firing pin. A certain amount of manual effort is required in drawing back the forearm and action bar in order 35 to perform the several operations of breech retraction, shell extraction, and cocking of the firing pin by a single movement of the forearm. It is obviously desirable that the amount of manual effort required be kept 40 within low limits, and also that this effort may be exerted smoothly throughout the stroke of the action.

The present invention aims to provide devices interposed between the action bar lug 45 and the cocking head effective to provide a smoothly operable action wherein the effort required to manipulate the forearm is considerably reduced, as compared with that required in prior constructions.

50 These and still further objects are to be at-

tained from a practice of the present invention, as will be apparent from the following specification of which the accompanying drawings form a part.

In the drawings:

55 Figure 1 is a fragmentary longitudinal elevation, partly in section, of a firearm embodying the present invention.

Figure 2 is a longitudinal elevation, partly in section, of the breech block illustrated 60 in Figure 1, the parts being shown in fired position.

Figure 3 is a view of the breech block similar to that of Figure 2 but showing the parts in a position where cocking of the 65 firing pin takes place.

Figure 4 is a longitudinal section of the breech block taken along the line 4-4 of Figure 1.

Figure 5 is a diagrammatic illustration as 70 viewed from below showing the arrangement of parts associated with the breech block, the breech block itself, however, being removed for clarity of illustration.

Figure 6 is a detail view in side elevation 75 of the action bar lug and rearmost end of the action bar.

A firearm of the type to which the preferred embodiment of my invention is applied is shown in Figure 1. This firearm 80 embodies a barrel 10, a magazine 11, and a receiver 12 having a shell ejection port 13 and containing the mechanism for shell feeding and ejection, firing mechanism, etc., similar in general aspects to the firearms of the 85 above-mentioned patents. A breech block 14 is adapted to seat behind a shoulder 15 provided in the upper portion of the receiver to firmly hold a shell in the barrel chamber for firing. An action bar lug 16, 90 formed integral with the rear end of an action bar 17, is adapted to ride in a cam groove 18 which extends rearwardly and upwardly, in the side of the breech block. A forearm or handle 30 secured to the action 95 bar and slidable on the magazine tube 11 is provided to enable manipulation of the action bar. On rearward movement of the action bar, the lug 16 will be caused to contact the rear face of the cam groove 18 and 100

cam the breech block downwardly from its position behind shoulder 15, whereupon further movement of the action bar will cause a retraction of the breech block, at the same time effecting the functions of shell extraction and ejection, as well as cocking of the firing mechanism. A firing pin 19, suitably housed in the breech block and mounted in bearings at 42 and 43 for longitudinally 10 slideable movement therein, is spring urged toward firing position and is provided with a rearwardly and downwardly extending cocking head 20.

During the rearward movement of the action bar lug 16 and consequent retraction of the breech block, cocking of the cocking head 20 and firing pin 19 will be effected by devices constructed according to the present invention, as will now be described. Referring to Figure 2 the forward face of the cocking head is seen to be provided with a flat surface at 21. This surface 21 is adapted to be engaged by a cam surface 22 provided on a cam lever 23 pivoted to the breech block 24 and formed with a forwardly extending nose 25. The nose 25 is adapted to be engaged by an inwardly projecting portion 26 (Figures 5 and 6) integral with the action bar lug 16, causing an upward pivotal movement of member 23 around pivot 24 on rearward movement of the action bar. During such rearward movement of the action bar, the cocking head 20 and firing pin 19 will be moved rearwardly from the position shown 30 in Figure 2 to that shown in Figure 3, whereupon a notch 27 formed on the cocking head 20 will be engaged by the nose of a sear 28 also pivoted at 24 and spring pressed at 29 to normally urge the sear into cocking head engaging position. The sear 28 is formed with a rearwardly and laterally projecting portion 31 adapted to be engaged by a forwardly projecting nose on a trigger 32. During the rearward movement of the action bar, the 40 projection 26 on lug 16 will exert a camming action on the nose 25 and cause a pivotal movement of the lever 23 about pivot 24, whereupon engagement of the cam surface 22 with the surface 21 of the cocking head 20 will effect cocking. It will be seen that the leverage arm between the point of contact of lug projection 26 and the pivot 24 is considerably greater than the leverage arm between the pivot 24 and the point of contact between the cam surface 22 and the cocking head. The 50 mechanical advantage thus afforded is augmented partly by the camming action between the lug projection 26 and the nose 25, and partly by the camming action between the cam surface 22 and the abutment 21, enabling operation of the action smoothly and without the exertion of an undue amount of manual effort.

On returning the forearm to its forward position, the breech block will be moved for-

ward and upward to its position in front of the barrel chamber, the rear portion of the breech block then occupying its seat in front of shoulder 15 of the receiver frame. During this forward movement of the breech block the action bar lug 16 will be moved from the position of Figure 3 to the position of Figure 1, relative to the breech block, and by the release of rearward pressure against lever 23 by the lug 16, the lever 23 will move by gravity from the position of Figure 3 to the original position of Figure 1. The firing pin 19 will however be left in its cocked position until released by the trigger operated sear 28. After firing, the parts will be returned to the position of Figure 1 ready for another cycle of operation. If desired, the lever 23 may be provided with spring means, suitably arranged, to assist in returning the lever from the position of Figure 3 to the position of Figure 1, although this is not necessary to its successful operation.

An action bar recoil lock is preferably provided to prevent rearward movement of the breech block until after a cartridge has 90 actually been fired. Such mechanism, however, forms no part of the present invention except insofar as it is interrelated with the devices of the present invention. For a more detailed description of such mechanism, 95 reference may be had to the patent to Loomis, No. 1,579,177, above mentioned. Parts of the locking mechanism disclosed in said patent are illustrated in Figures 4 and 5 of the present drawings to show their relation to 100 the devices of the present invention. In Figure 5 are shown parts of the firing mechanism housed within the breech block as would be seen from the bottom with the breech block itself removed. A transversely slideable locking pin 33 is provided at one of its ends with a notch presenting a locking shoulder 34 adapted to engage the rear portion 35 of the projection 26 on action bar lug 16 (Figure 6), for the purpose of locking the action bar against rearward movement when the gun is in "ready to fire" condition. The locking pin is urged into engagement with the projection 26 by a member 36 pivoted at 37 and engaging the end of locking pin 33 at the 110 opposite side of the breech block from the action bar. An element 38, pivoted at the rear end of member 36, is spring urged to the position shown in Figure 5 where it lies in the path of a flange indicated by broken lines at 39, which flange is integral with and takes part in the movement of the cocking head 20. It will be seen that when the firing pin is in 120 cocked position, flange 39 will urge the element 38 and member 36 about pivot 37 to cause locking pin 33 to move into locking engagement with the barrel lug. By this movement of member 36 a locking portion 40 on member 36 will be moved out of locking 125 engagement with a lug 41 integral with sear

28 to unlock the sear and permit the cocking head to be released by the sear upon depression of the trigger. For a more detailed explanation of a locking mechanism of this type reference may be had to the Loomis patent 5 above-mentioned. It will be seen that the improved cocking devices of the present invention are positioned in the breech block to perform their functions effectively without interfering with the operation of the various other devices also housed in the breech block, and that the various devices may operate in efficient cooperation with each other.

10 It will be understood that various changes 15 may be made in the construction and arrangement of parts without departing from the spirit of the present invention as defined in the following claims:

What I claim is:

20 1. In a firearm, in combination, an action bar having a lug integral therewith, a reciprocable breech block formed with a groove accommodating said lug for actuation of the breech block, a firing pin housed in said breech block, means for cocking said firing pin comprising a cocking head integral therewith and a lever pivoted on said breech block engageable with said cocking head and having a portion positioned in said groove for actuation 30 by said action bar lug.

25 2. In a firearm, in combination, an action bar having a lug integral therewith, a reciprocable breech block formed with a groove having a curved portion accommodating said 35 lug for actuation of said breech block vertically and longitudinally on movement of said action bar, a firing pin carried by said breech block, and means for cocking said firing pin comprising a lever pivoted on said 40 breech block and having a portion engageable with said firing pin and another portion positioned in the curved portion of said groove for actuation by said action bar lug.

3. In a firearm, in combination, an action 45 bar having a lug integral therewith, a reciprocable breech block formed with a groove having a curved portion accommodating said lug for actuation of said breech block vertically and longitudinally on movement of 50 said action bar, a firing pin carried by said breech block, and means for cocking said firing pin comprising a cocking head integral with said firing pin and a lever pivoted on said breech block having an upwardly projecting portion engageable with said cocking 55 head and a forwardly projecting nose positioned in the curved portion of said groove for actuation by said action bar lug.

4. In a firearm, in combination, a reciprocable breech block, a firing pin housed therein, a cocking head integral with said firing pin, a lever pivoted on said breech block having a portion engageable with said cocking head, an action bar having a lug integral therewith engageable with said lever, and an action bar

locking mechanism comprising a locking pin carried by said breech block engageable with said lug and means governed by movement of said cocking head for controlling said locking pin.

5. In a firearm, in combination, an oscillating and reciprocating breech block, a firing pin housed therein, a cocking mechanism comprising a cam lever pivoted on said breech block and having a portion engageable with said firing pin, the effective length of the lever arm thus engaging the firing pin varying during the movement of the firing pin thereby; and an action bar adapted to oscillate 70 said breech block and having a portion engageable with said lever to rock said lever during the oscillatory movement of said breech block.

6. In a firearm, in combination, a reciprocable breech block, a firing pin housed therein, a cocking mechanism comprising a cocking head integral with said firing pin, a cam lever pivoted on said breech block having a portion engageable with said cocking head, an action bar and a lug integral therewith engageable with said lever, the effective length 80 of the lever arm thus engaged by the action bar lug decreasing during a part of the firing pin cocking movement of said lever.

7. In a firearm, in combination, a reciprocable breech block, a firing pin housed therein, a cocking mechanism comprising a cocking head integral with said firing pin, a cam lever pivoted on said breech block having an upwardly projecting portion engageable with 85 said cocking head, an action bar and a lug integral with said action bar engageable with said lever, the arrangement of the cam surfaces on said lever being such that the effective length of the lever arm in engagement 90 with the cocking head is increased and the effective length of the lever arm engaged by said action bar lug is decreased during the firing pin cocking movement of said lever.
